UNITED STATES PATENT OFFICE

155,022

DESIGN FOR AN ENVELOPE MOISTENER

Russell McKamen, Chicago, Ill.

Application August 31, 1948, Serial No. 148,378

Term of patent 14 years

(Cl. D74—10)

To all whom it may concern:

Be it known that I, Russell McKamen, a citizen of the United States, residing at Chicago, in the county of Cook and State of Illinois, have invented a new, original, and ornamental Design for an Envelope Moistener, of which the following is a specification, reference being had to the accompanying drawing, forming part thereof.

In the drawing:

Fig. 1 is a side view of an envelope moistener, showing my new design, and

Fig. 2 is a plan view.

I claim:

The ornamental design for an envelope moistener, as shown.

RUSSELL McKAMEN.
